C J Woolson Design Drawing

From The R. Jones Library

Des. 186

No. 2. C. J. Woolson, Cleveland, Ohio.

Letters Patent Design No. 136, dated 7 July 1837.

The schedule referred to in these Letters Patent and making part of the same.

To all whom it may concern; Be it known that I, C. J. Woolson of Cleveland in the County of Cuyahoga, and State of Ohio, have invented and produced a new and useful design for the side plate of a stove, which is applicable most particularly to that kind of stove for heating apartments usually called a Box Stove; and I do hereby declare that the following is a full and exact description thereof, reference being had to the accompanying drawings in which the ornamental design thereon is clearly represented.

On the centre of the plate is the bust of a man, in relief, as shown at A; and at either end of the panel containing said figure is the ornamental scroll work, and leafing B, B, surrounding this panel is the ornamental wreath of flower work C, C. Near the outer edge of said plate is the border of shell work D, D, the respective ornaments being arranged as represented.

Having thus distinctly shown and described the nature and arrangement of the ornaments, and figures upon my side plate for a stove; what I claim therein as new, and desire to secure by Letters Patent is the configuration and arrangement of said ornaments as herein designated and represented.
